UNITED STATES PATENT OFFICE

ALFRED E. VONGUNTEEN, OF HAMILTON, ONTARIO, CANADA, ASSIGNOR, BY DIRECT AND
MESNE ASSIGNMENTS, TO THE COLUMBUS DENTAL MANUFACTURING COMPANY, OF
COLUMBUS, OHIO

ARTIFICIAL TOOTH

Application filed December 18, 1923. Serial No. 681,371.

The present invention relates to artificial teeth and more particularly to the type of artificial teeth used for replacing individual natural teeth which have been removed or destroyed. This type of artificial tooth ordinarily comprises a metal backing which is secured in the denture by a crown or bridge-work, together with a porcelain facing whose principal function is to simulate a natural tooth in appearance.

The object of the present invention is to provide an improved form of artificial tooth of considerable strength and good appearance, which can be easily placed in position without requiring excessive skill on the part of the practitioner.

With this object in view, one feature of the invention consists in the provision of a backing adapted to bear the entire biting stress so that none of the stress falls on the facing. Also, according to the invention, the facing is provided with grooves adapted for engagement with the backing and arranged to permit the facing to be inserted into the backing from the cutting line of the tooth. Thus a preformed backing may be set in the proper position formerly occupied by the natural tooth, and a facing of suitable size inserted and firmly cemented to the backing so that the use of anchoring pins or similar securing devices is entirely eliminated.

Another feature of the invention consists in the formation of the porcelain facing with an integral root which is adapted to fill the root cavity whenever an entire natural tooth has been removed. In such a case the backing is secured in position, as by a suitable bridge-work, so that upon the insertion of the facing therein, the integral root takes its proper position inside the cavity.

In the accompanying drawings Fig. 1 is a plan view of a portion of a natural jaw in which two of the improved artificial teeth are supported by bridge-work; Fig. 2 is a side elevation of the jaw with the metal backings of the artificial teeth supported between two natural teeth; Fig. 3 is a view similar to Fig. 2 but showing the complete artificial teeth set in place; Fig. 4 is a rear view of the artificial tooth without a root; Fig. 5 is a section on

line 5—5 of Fig. 4; Fig. 6 is a section on line 6—6 of Fig. 4; Fig. 7 is a rear elevation of an artificial tooth with an integral root; and Fig. 8 is a sectional elevation of the tooth shown in Fig. 7.

The tooth illustrated in Fig. 4 comprises a metal backing 10, and a facing 12 of such material as to simulate a natural tooth in appearance. According to the usual practice, the backing is preferably of gold and the facing of porcelain. The backing is provided with a pair of dovetailed tongues 14 bent inwardly and sloping toward each other from the cutting line to the gum line of the tooth, while the facing is provided with similarly formed grooves adapted for engagement with the tongues of the backing. The tongue and groove connection is designed so that when the facing is firmly seated in the backing the cutting or incisal edge 13 of the backing lies substantially flush with the edge of the facing in order that the entire biting stress may be taken by the backing, thus permitting the facing to carry out its sole purpose of appearing like a natural tooth and precluding any injury to the facing through biting stresses. In order to insure placing the entire stress on the backing, the latter may project slightly over the edge of the facing, if desired. The upper end of the facing (or the lower end in case of a tooth for the lower jaw) has a projection 16 adapted to lie against the gum to give the appearance of a natural tooth rising from the gum. The facing is firmly cemented to the backing, thus serving to hold the parts together without any of the usual forms of anchoring pins. This form of tooth is adapted for use where no root cavity is to be filled, as for example, where the gum has contracted to close up the cavity after a tooth has been removed.

The tooth illustrated in Fig. 7 is similar to the above, except that the facing, which is indicated at 17, is provided with an integral root 18 adapted for filling a root cavity. The backing 20 is curved, as illustrated in Fig. 8, in order to cause the cutting edge of the tooth to come in proper position, and at the same time to permit the root to fill the root cavity when the facing is inserted. The backing and

facing are provided with a dovetailed tongue and groove and are so arranged that the cutting edge of the backing takes the entire biting stress, as before.

5 The above described teeth are herein illustrated as embodied in a bridge-work for supplying two adjacent artificial teeth in a natural denture. In Fig. 2 are illustrated two backings 10 and 20 supported between two 10 natural teeth 22 and over the gum 24. The backing 10, which has no provision for holding a facing with a root, is mounted over a portion of the jaw where there is no root cavity whereas the backing 20 is mounted 15 over the root cavity 26 in the gum. The backings 10 and 20 are soldered together and also to crowns 28 and 30 on the adjacent natural teeth. The backings are supported entirely 20 clear of the gum line so that no metal rests against the gum. The facings are then 25 inserted as described above, suitable cement being used to effect a bond between the facings and backings. The projection 16 on the facing 12 is sufficiently long to rest directly 30 against the gum, as shown in Fig. 3, so that the tooth has the appearance of a natural tooth rising directly out of the gum. The facing 17 is inserted so that the root 18 enters and fills the root cavity 26.

35 It will be seen that the present invention forms a convenient and economical method of inserting artificial teeth. Although the specific embodiment of the invention has been described as for bridge-work, the invention 40 may obviously be modified without departing from its broader aspects to include other forms of mounting, such as by a crown over a root which has been left after the partial destruction of a tooth. The backings and facings may be entirely preformed so that the 45 practitioner may keep a supply of the sizes and shapes ordinarily required, thus eliminating the necessity of making up each tooth separately, as is required under existing methods. The use of the usual anchoring 50 pins, which tend to weaken the facing and permit it to loosen in the backing is entirely eliminated by the present invention. Inasmuch as the surfaces of the backing and facings lie substantially flush with one another, no bending of the backing over the facing is 55 desirable or necessary, so that the facing may be conveniently removed for repairs or replacements without damaging the backing. Furthermore, since the facing is inserted from 60 the cutting line rather than from the gum line of the tooth, the insertion may be made after the backing is completely set up in position in the denture. Thus all the preliminary 65 steps such as soldering the backings and crowns may be carried out before the facing is inserted, without danger of injuring the facing.

What is claimed is:

65 1. An artificial tooth having an integral

root and comprising a metal backing, means for supporting the backing in proper position with the metal clear of the gum line arranged to have its incisal surface bear the entire biting stress, a facing adapted to simulate a natural tooth and having external grooves for engaging the backing and adapted to be cemented thereto, whereby the use of anchoring pins is eliminated.

2. An artificial tooth for a bridge-work 70 comprising a metal backing, means for supporting the backing from a natural tooth with the metal clear of the gum line and having its incisal surface adapted to bear substantially the entire biting stress of the tooth, a porcelain facing having grooves of greater depth at the lingual end than at the labial end for permitting engagement with the backing and provided with an integral root adapted to be inserted into the backing from the cutting 75 line of the tooth, the facing and backing being cemented together, whereby the use of anchoring pins for securing the backing and facing is eliminated.

3. An artificial tooth comprising a facing 80 having an integral root extension and a crown portion, said crown portion being provided with a labio-occlusally inclined surface, a tenon projecting from said inclined surface and having its vertical sides under cut; said tenon being of greater depth at the lingual 85 end than at the labial end; a cusp plate, said cusp plate being provided with a mortise to fit said tenon.

4. In an artificial tooth having a root section, a backing having a pair of dovetailed tongues bent inwardly and sloping toward each other from the cutting line to the gingival end of the backing and terminating short of the gum line of the tooth.

5. In an artificial tooth having a root section, a backing having a pair of dovetailed tongues bent inwardly and sloping toward each other from the cutting line to the gingival end of the backing and terminating short of the gum line of the tooth, and a porcelain body having grooves in its lingual face complementary with the said backing designed for engagement with said tongues.

6. In an artificial tooth having a root section, a backing having a pair of dovetailed tongues bent inwardly and sloping toward each other from the cutting line to the gingival end of the backing and terminating short of the gum line of the tooth, and a porcelain body having grooves in its lingual face complementary with the said backing designed for engagement with said tongues, the incisal end of the backing lying substantially flush with the incisal end of the porcelain body.

7. An artificial tooth comprising a backing having a pair of dovetailed tongues bent inwardly and sloping toward each other from the incisal end to the gingival end of the

backing, and a porcelain facing provided with an integral root, grooves in the lingual face of said facing complementary with said tongues on the backing and designed to receive said tongues, said grooves and tongues terminating short of the gum line of the tooth.

8. In dental bridgework, abutment castings, and pontics, said pontics each comprising a root tooth and an occlusal attachment therefor, said attachment presenting the morsal surface of the pontic, the gingival surface of said attachment and the opposite surface of the root tooth being on an incline sloping downwardly from the lingual surface of the pontic to the labial face thereof, together with side members on the attachment and side cut-outs on the root tooth conforming to the opposed surfaces of said side members.

9. In dental bridgework, abutment castings, and pontics, said pontics each comprising a root tooth and an occlusal attachment therefor, the opposed surfaces of said attachment and said root tooth being disposed at an incline sloping downwardly from the lingual surface of the pontic toward the labial face thereof, said root tooth furthermore having entrant cut-outs at the sides forming a dovetail on the root tooth at the morsal end, said dovetail extending from the lingual surface of the root tooth and vanishing adjacent the labial face of the root tooth; together with members on said attachment at the sides thereof corresponding with the vanishing dovetail formation of said root tooth.

10. A pontic comprising a root tooth and a cusp, a key integral with and on the occlusally directed surface of the tooth having sides sloping inwardly toward each other from the incisal end toward the lingual face of the tooth and wedgedly engaging the cusp portion, said key and cusp terminating short of the gum line of the tooth.

11. A root tooth having a key integral with and on its occlusally directed end surface, said key terminating short of the gum line of the tooth and having sides sloping inwardly toward each other from the incisal end toward the lingual face of the tooth, and adapted to wedgedly engage a cusp.

12. A root tooth having a key integral with its linguo-occlusally directed surface, the sides of said key sloping inwardly toward each other from the occlusal end toward the lingual face of the tooth, and a cusp member complementary to and adapted to wedgedly engage said key, said key and key way terminating short of the gum line of the tooth.

ALFRED E. VONGUNTEM.
